RECORD RECEIVING DEVICE

Edward Kirby Bottle, Elmira, N. Y., assignor, by
mesne assignments, to American Sales Book
Company, Inc., a corporation of Delaware

Application January 28, 1930, Serial No. 424,101

2 Claims. (Cl. 282—12)

This invention relates to improvements in record assemblies of the type employing long continuous record and transfer strips in interleaved transfer relation with each other and adapted for use in various types of typewriting machines, billing machines and the like, or for manual transfer inscription.

It is a general object of the invention to provide a record receiving device or manifolding assembly of long continuous record and transfer strips arranged in transfer relation with each other and having improved means whereby sets of inscribed record and transfer leaves severed from the assembly may be quickly and expeditiously separated from each other.

A further object of the invention is to provide an improved manifolding assembly of the class mentioned, whereby one of the transfer leaves of a severed set of inscribed record and transfer leaves may be quickly and easily separated or stripped from the other transfer leaves of the set and remain in position with the severed inscribed record leaves for the purpose of effecting supplemental transfer inscription to one of the severed record leaves.

Other objects of the invention will be in part pointed out in the following detailed description of certain illustrative but preferred embodiments of the invention and will be in part obvious therefrom.

The invention accordingly comprises the features of construction, combination of elements and arrangement of parts, which will be exemplified in the construction hereinafter set forth and the scope of the application of which will be indicated in the claims.

For a more complete disclosure of the nature and advantages of the invention reference is had to the following detailed description and to the accompanying drawing in which:

Fig. 1 is a partially diagrammatic perspective view of a fragment of a manifolding assembly embodying the invention;

Fig. 1A is a perspective view similar to Fig. 1 but viewing the assembly from the opposite side;

Fig. 2 is a similar view of a different form thereof, and

Fig. 3 shows a sheet which forms a part of the assembly.

As shown in Fig. 1, long continuous record strips 5, 6, 7 and 8 are relatively superposed and interleaved with long continuous transfer strips 9, 10 and 11. The transfer strips may be of ordinary carbon paper and serve to duplicate

upon record receiving strips underlying them the matter inscribed upon the uppermost strip 5.

As shown, the record and transfer strips are sub-divided at equally longitudinally spaced intervals therealong by weakened transverse severance lines 12, which may be provided by scoring or otherwise weakening the strips to severance in any well known manner. These weakened severance lines 12 in the record and carbon strips are preferably arranged in groups depthwise of the assembly, thus dividing the latter into a multiplicity of groups or sets of interleaved record and transfer leaves, the top leaf of which is the original record leaf receiving the original inscription. The complete assembly of record and transfer strips may be disposed in any desirable manner for convenient handling as in the form of a supply roll but it is preferred to form it into a zigzag folded supply pack. When thus folded into a supply pack the folds of the pack may coincide with the groups of severance lines 12.

Usually, after the original or upper sheet of an end set of record and transfer leaves has been inscribed this sheet, and the leaves or sheets underlying the same, are separated from the strips of which they form end portions. This severance may be achieved by severance along the respective groups of weakened severance lines 12 as desired and may be assisted, for example, by a tearing bar (not shown). Upon severance of an inscribed set of record and transfer leaves the separation of the record leaves from the transfer leaves may be accomplished conveniently by forming the record receiving strips with cut-out portions. In the present exemplification these cut-out portions are positioned at the corners of the sheets contiguous to the severance lines as indicated at 13. The carbon strips are likewise formed with cut-out portions or apertures 14 disposed at points of the respective sheet sets spaced with regard to the cut-out portions 13 of the record receiving sheets. It will thus be seen that selective grip formations are provided in each leaf set and spaced apart thereon. Thus, an operator grasping the projecting marginal portions of the carbon sheets at the cut-outs 13 of the record sheets, and at the same time grasping the projecting marginal portions of the record sheets at the cut-outs 14 of the carbon sheets, may subdivide or strip the record and carbon sheets of a severed set into two different groups. However, according to the present invention, these two groups of separated leaves need not contain solely carbon or record sheets. For example, as shown in Figs. 1 and 1A, the transfer

strips or webs 9 and 11 are not cut away at parts thereof corresponding to the cut-out portions 13 of the record strips, while the transfer web 10 is provided with such cut-out portions 5 proportioned and positioned exactly as in the case of the cut-outs 13 of the record strips. Also, while the record strips 5, 6 and 7 are provided with the cut-outs 13, the bottom record strip 8 has its edges extending in line with the edges 10 of the carbon strips 9 and 11, or in other words, the record strip 8 is formed with cut-outs corresponding to and positioned exactly as the cut-outs 14 of the carbon strips 9 and 11. Consequently, with this arrangement and positioning 15 of the cut-outs of the several strips, the group of severed sheets containing the sheets torn from the strips 5, 6 and 7 will also include the sheet torn from the strip 10, while at the same time the group, including the sheets torn from the strips 20 9 and 11, will also include the bottom sheet, torn from the strip 8.

The desirability of this function will be apparent since it is very often required, after the main inscribing operation and separation of the 25 sheets, to have an underlying record receiving sheet of the record group arranged so that additional or supplemental data may be inscribed thereon as this supplemental data is written upon the uppermost sheet subsequently to the separation 30 of the inscribed sheets into two groups. In connection with the carbon group, the lowermost record sheet torn from the strip 8 may serve as a partition or separating member to isolate the group from succeeding groups associated therewith and may also serve for identification purposes. While in the present instance, for the sake of conciseness, there has been shown one carbon leaf which remains in association with the group composed mainly of inscription receiving sheets, and while there has also been shown one inscription receiving sheet remaining in association with the group composed mainly 40 of carbon leaves, it is obvious that any number of "casual" sheets might be included in each 45 group or that one group might be composed solely of, for example, carbon leaves or inscribed sheets.

In Figure 2 the invention has been disclosed in association with a record assembly of the fan-fold type. Thus, the inscription receiving paper or other material is folded longitudinally of its direction of movement to provide inscription receiving webs 15 to 18, and dispose between the folds defining these several webs are carbon or 50 transfer strips 19, 20 and 21. Obviously, due to the construction of the record receiving body, it will be impracticable to provide the cut-out parts or grip escaping apertures. As shown, the record receiving surfaces, as well as the layers of 55 transfer material, may be provided with transverse lines of fold 22 which may additionally be defined by lines of scoring to facilitate the separation of an end group or pile of sheets from the main body of the webs. The lines of scoring provided in the carbon strips 19 and 20 have longitudinally deviating portions such that bulged portions or grip tabs 23 are furnished which necessarily afford complementary portions in the form of recesses or vacuities 24. However, according to the present invention, the carbon strip 70 21 will preferably be formed with straight score lines. Accordingly, a pile or set of record and carbon leaves is presented, after severance, which an operator may separate into different groups by simply grasping the inscription receiving body at

points within the recesses 24 and also grasping the projecting portions or grip tabs 23 and moving the grasped parts in different directions. Thus, one pile of record receiving material, together with a transfer leaf or sheet 21, will be found in one group and solely—in the present exemplification—carbon leaves 19 and 20 will be found in the other group. Accordingly, the record receiving device is now in condition whereby matter additional to that previously inscribed may be 10 filled in on the uppermost layer or web 15 and this matter will not appear upon the layers or webs 16 and 17, but will be duplicated on the face of the web 18.

In the embodiment of the invention disclosed 15 in Fig. 2 it will be noted that the longitudinally deviating portions of the carbon strip transverse severance lines are positioned intermediate the lengths of said lines, and that the grip tabs 23 and vacuities 24 are accordingly positioned at 20 points inwardly spaced from both of the opposite longitudinal assembly edges. In this manner, the grip tabs 23 are protected in the complete assembly from damage due to handling of the record supply assembly. A further advantage of 25 this arrangement is that the tearing operation in severing an inscribed set of record and transfer leaves may be initiated at either of the opposite longitudinal assembly edges. In this connection, it will be further noticed that the ends of the severance lines where tearing is initiated at either of the opposite assembly margins are positioned substantially in aligned relation with each other depthwise of the assembly so as to promote correct starting of the tearing operation and avoiding 30 tearing of the record and carbon strips except at the severance lines.

In both of the illustrative embodiments above particularly set forth, it will be noticed that the structure or structural features of the record and carbon strips provided by the cut-outs 13 and 14 of the embodiment of Fig. 1, and those provided by the relative positioning of the transverse severance lines of the record and carbon strips including the longitudinally deviating portions of the carbon strip severance lines to provide the grip tabs 23 of the embodiment of Fig. 2, result in producing the selective grip formations positioned at opposite parts of a severed set of record and transfer leaves. Thus in a severed set of 40 leaves in either of the disclosed embodiments, the transfer leaves have parts or grips extending beyond the contiguous marginal portions of the superposed record strips, while in another part of the set the record leaves have marginal portions 45 or grips extending outwardly from the adjacent portions of the superposed transfer leaves. The grips of the record leaves may thus be selectively engaged and at the same time the grips of the carbon leaves may be selectively engaged and the 50 severed set thus quickly and easily separated into two different groups by exerting a pull in opposite directions. It should be noted, however, that in either embodiment one of the carbon leaves may be selectively gripped and stripped from the 55 other carbon leaves so as to remain in interleaved transfer relation with the separated group of record leaves, thus providing for the supplemental transfer inscription described in detail 60 above.

Since certain changes may be made in the above construction and different embodiments of the invention could be made without departing from the scope thereof, it is intended that all matter contained in the above description or shown in 70

the accompanying drawing shall be interpreted as illustrative and not in a limiting sense.

Having described my invention, what I claim as new and desire to secure by Letters Patent is:

5 1. In a manifolding assembly, in combination, a plurality of long continuous record strips and a plurality of long continuous transfer strips in interleaved transfer relation with each other, said record and transfer strips having longitudinally spaced transverse weakened severance lines, said weakened severance lines being arranged in depthwise groups in the assembly for simultaneous severance of the strips into sets of record and transfer leaves in interleaved transfer relation, said record and transfer strips having structural features therein positioned respectively at said groups of transverse weakened severance lines and including marginal grip portions of record leaves of respective sets extending 10 outwardly beyond adjacent edges of one or more but not all of the transfer leaves of the same sets, and including also marginal grip portions of one or more but not all of the transfer leaves extending outwardly beyond adjacent edges of record leaves, said structural features thus providing upon severance along said lines spaced selective grip formations for each set of leaves whereby the record leaves of a severed set may be simultaneously gripped at one part of the set to the exclusion of certain but not all of the transfer leaves and whereby certain but not all of the transfer leaves may be simultaneously gripped at another part of the set to the exclusion of the record leaves, said structural features of one of 15 said transfer strips being substantially the same and similarly positioned at each of said leaf sets as the corresponding structural features of the record strips, whereby when a set of leaves is severed from the assembly the transfer leaf severed from said last mentioned transfer strip has its said grip portion positioned in depthwise alignment with those of the severed record leaves of the same set so as to be simultaneously gripped with the latter, thus removing one transfer leaf

of a severed set with the record leaves thereof and in interleaved transfer relation therewith.

2. In a manifolding assembly, in combination, a plurality of long continuous record strips and a plurality of long continuous transfer strips in interleaved transfer relation with each other, said record and transfer strips having longitudinally spaced transverse weakened severance lines, said weakened severance lines being arranged in depthwise groups in the assembly for simultaneous severance of the strips into sets of record and transfer leaves in interleaved transfer relation, said transverse weakened lines of certain but not all of said transfer strips including longitudinally deviating parts spaced inwardly from the opposite ends of the lines thus forming, upon severance along said lines, grip tabs spaced inwardly from each of the opposite longitudinal strip edges and projecting from the severed edges of the strips for selective gripping thereof, and also forming corresponding recesses or vacuities in the adjacent severed strip edges, the said transverse severance lines of said record strips and one of said transfer strips being substantially straight and forming outer boundaries of rectangular record and transfer leaves and providing, upon severance along said lines, marginal grip portions of the record and transfer leaves in depthwise alignment with said recesses or vacuities so that they may be selectively gripped through the recesses, said grip tabs of the transfer leaves of a severed set, and said grip portions of the record leaves of one transfer leaf thereof, being thus spaced apart whereby the leaves of the severed set may be selectively gripped at spaced parts of the set, certain but not all of the record leaves at said grip tabs and the record and one transfer leaf at said grip portions thereof through said recesses, thus providing for separation of some but not all of the transfer leaves from the record leaves while a transfer leaf remains in interleaved transfer relation with the record leaves.

EDWARD K. BOTTLE.
